YARN SPINNING STAND

Robert M. Oliver, 5893 Baseline Road,
Boulder, Colo. 80303

Filed Mar. 1, 1972, Ser. No. 231,073

Term of patent 14 years

Int. Cl. D15—06

U.S. Cl. D92—15

FIG. 2

FIG. 1

FIG. 3

FIG. 4

FIG. 5

FIG. 6

FIG. 7

FIG. 1 is a perspective view of a yarn spinning stand showing my new design;

FIG. 2 is a top plan view thereof;

FIG. 3 is a right side elevational view thereof;

FIG. 4 is a bottom plan view thereof;

FIG. 5 is a front elevational view thereof;

FIG. 6 is a rear elevational view thereof;

FIG. 7 is a left side elevational view thereof.

I claim:

The ornamental design for a yarn spinning stand, as shown.
